UNITED STATES PATENT OFFICE.

WILLIAM L. CARTER, OF WATERLOO, IOWA, ASSIGNOR TO WATERLOO REGISTER COMPANY, OF WATERLOO, IOWA, A CORPORATION OF IOWA.

AIR REGISTER.

Application filed June 7, 1926. Serial No. 114,258.

This invention relates to an air register, primarily intended for use in a heating or ventilating system for buildings, and preferably set in the wall of the room, near the 5 floor.

The general object of the invention is to provide a register in which the shutters, when open, will have the same appearance as a fixed bar design or grating, permitting 10 the free passage of a maximum current of hot air therethrough, and will, when closed, present an attractive panel effect with a polished surface, which may easily be kept 15 clean and sanitary. In the preferred form of the invention, the frame containing the shutters is removably secured in an outside frame, which is secured at the outlet of the stack or flue, between abutting ends of the base board.

20 The specific construction of the invention and the advantages resulting therefrom will be more particularly described in connection with the accompanying drawing, which illustrates the same in its preferred form.

25 In the drawing:

Figure 1 is a front elevation of the invention, the view being broken and the upper part closed, while the lower part is open.

Figure 2 is a vertical section through the 30 register as shown in Figure 1.

Figure 3 is a horizontal section looking downwardly with the register closed.

Figure 4 is a horizontal section looking upwardly with the register open.

35 Figure 5 is a detail perspective view, showing a portion of one of the shutters and the means for controlling the same.

In the form shown in the drawing, the register comprises an outer rectangular frame 10, made from strips of metal, channel-shaped in cross section, and secured together at the corners by welding, or other suitable means. The inner portion of the frame 10 is bent inwardly, as at 11, to form 40 a seat for receiving the inner frame 12. Lugs 13 are pressed out of the lower rail of the outer frame 10, and the lower edge of the frame 12 is held by the lugs 13 against the seat 11, while the upper edge of the frame 12 is secured to its seat by screws 14.

45 The inner portion of the frame 12 is turned inwardly to form peripheral flanges 15, within which the shutters 16 are located. One edge of each shutter is rolled about a 50 rod 17, which is secured to flanges 15 at the

top and bottom of the frame, and constitutes a hinge rod about which the shutter is rotatable. The other edge of each shutter is offset to form a lip 18, adapted to engage the rolled edge of the next shutter when the 55 register is closed. One end of each lip 18 is cut and bent into a horizontal plane to form an ear 19, which is pivoted on a pin 20, integrally welded, or otherwise secured, to a horizontal bar 21. The ends of some or 60 all of the pins 20 are upset sufficiently to prevent the bar 21 from becoming separated from the shutters. The edges 22, from which the ears 19 are cut, form shoulders which are engageable by the bar 21 to limit 65 the opening movement of the shutters. A finger 23, secured to one of the shutters, affords a convenient means for opening and closing the register.

70 When the register is open, it will be noted that all of the shutters are in planes perpendicular to the face of the register, and the rolled edges thereof have the same appearance as the ordinary fixed bar design or grating, beneath which a valve or shutter is 75 placed. The present construction, however, has the advantage that when the shutters are closed, they constitute, in effect, a series of panels. The surface of these panels, as well as the surface of the frames surrounding 80 them, is highly polished, so that it not only presents an attractive appearance but affords 85 no place for dust to collect, so that it may easily be kept clean and sanitary.

90 While I have shown and described the specific construction of the invention in its preferred form, it is, of course, to be understood that the shape, relative dimensions and relative size may be considerably modified without any material departure from 95 the salient features of the invention as claimed.

What is claimed is:

1. In an air register, the combination of a rectangular frame, equi-distant rods secured thereto and extending across the opening therein, a series of shutters mounted on the respective rods, each shutter having one edge rolled about its rod to form a hinge connection therewith, and the other edge offset to fit beneath the rolled edge of the next shutter so as to present a panel effect when the shutters are closed and present the appearance of a fixed bar design when the shutters are open, one rear corner portion 100
- 105
- 110

of each shutter being slit longitudinally and bent at right angles to form a projecting ear, a bar having series of projecting pins on which the ears are pivoted, the edges from 5 which the ears are cut forming shoulders engageable by said bar to limit the opening movement of the shutters.

2. In an air register, the combination of an outer rectangular frame having the inner 10 portion of its face depressed to form a seat, an inner rectangular frame having a peripheral flange adapted to rest on said seat, means cooperating with said flange for removably securing it on the seat, equi-distant 15 rods secured to the inner frame and extending across the opening therein, a series of

shutters mounted on the respective rods, each shutter having one edge rolled about its rod to form a hinge connection, and the other edge offset to fit beneath the rolled edge of 20 the next shutter so as to present a panel effect when the shutters are closed and to present the appearance of a fixed bar design when the shutters are open, an ear formed at one corner of each shutter, a bar connecting the ears and pivoted thereto, and shoulders formed on the respective shutters and engageable by the bar to limit the opening movement of the shutters.

In testimony that I claim the foregoing as 25 my own, I have herto affixed my signature.

WILLIAM L. CARTER.
